UNITED STATES PATENT OFFICE.

FRANK ZALESKI, OF SOMERVILLE, MASSACHUSETTS, ASSIGNOR TO THE REECE
BUTTON HOLE MACHINE COMPANY, OF BOSTON, MASSACHUSETTS, A COR-
PORATION OF MAINE.

BUTTONHOLE-SEWING MACHINE.

1,152,466.

Specification of Letters Patent.

Patented Sept. 7, 1915.

Application filed November 6, 1914. Serial No. 870,697.

To all whom it may concern:

Be it known that I, FRANK ZALESKI, a subject of the Emperor of Germany, residing at Somerville, county of Middlesex, State of Massachusetts, have invented an Improvement in Buttonhole-Sewing Machines, of which the following description, in connection with the accompanying drawing, is a specification, like characters on the drawing 10 representing like parts.

This invention relates to buttonhole sewing machines and particularly to a device for guiding and controlling the stay cord that is frequently laid around the edge of 15 the buttonhole and over which the buttonhole stitches are formed.

The invention has particular reference to buttonhole sewing machines of that type which are known to the trade as the "Reece" 20 machines, and examples of which may be found in the following United States Letters Patent: No. 494,280, March 28, 1893; No. 498,216, May 23, 1893; No. 655,637, August 7, 1900. As will be seen by reference 25 to the above-cited patents, sewing machines of this type include a so-called stitch frame carrying an upper thread mechanism for manipulating the upper thread and an under thread mechanism (sometimes called a complementary stitch-forming mechanism) 30 for manipulating the under thread, and this under thread mechanism comprises a rotary block carrying the under needle for manipulating the under thread, a throat-plate 35 through which the needle operates, and other operative parts which it is not necessary to herein refer to. In machines of this type as heretofore built, the under thread extends up through the hollow spindle depending 40 from the block and is delivered from the upper end of the spindle to a tension device and under needle while the stay-cord has usually passed up outside of the rotary oscillatory block to a guide eye on the under 45 side of the clamp frame from which it is led into position to be attached to the buttonhole. During the operation of stitching a 50 buttonhole, the block carrying the under thread mechanism rotates about its axis, and in order to guide and hold the stay-cord properly during such rotary movement of the block it has been customary to form the

throat-plate with an annular groove in which the stay-cord will be laid as the block rotates.

I have herein improved the above construction by providing a means whereby the stay-cord is delivered upwardly through the spindle along with the under thread and is delivered from the upper end of the spindle 55 to a controlling device carried by the rotary block and rotatable therewith, which controlling device has a fixed position relative to the under thread mechanism so that the stay-cord will be delivered directly from the 60 controlling device to the throat-plate in any and all positions of the rotary block. This controlling device is also in the form of a cord-grip which permits the stay-cord to be drawn forward freely, but locks the cord 65 against backward movement. 70

In order to give an understanding of the invention I have illustrated in the drawings a selected embodiment thereof which will now be described, after which the novel features will be pointed out in the appended 75 claims.

Referring to the drawings, Figure 1 is a fragmentary sectional view showing a portion of a buttonhole sewing machine of the type illustrated in said above-mentioned 80 patents, said view showing the under thread mechanism in front elevation with the stay-cord grip secured thereto; Fig. 2 shows the opposite view of the under thread mechanism from that shown in Fig. 1 with some of the parts omitted; Fig. 3 is a section on the line $x-x$, Fig. 2; Fig. 4 is a section on the line $y-y$, Fig. 2; Fig. 5 is a plan view partly in section of the stay-cord grip. 85 90

Referring to Fig. 1 I have shown at 1 a portion of the usual clamp-frame of a buttonhole sewing machine of the type illustrated in the above-mentioned patents, said clamp-frame having removably attached 95 thereto the usual clamp-plates 2 and 3 to which the work is clamped and which constitute work-supporting means. 4 indicates the needle of the upper thread mechanism which is operated in usual manner, and 5 designates the rotary stitch block carrying 100 the under thread mechanism, said block being rotatably mounted in bearings 6, 60 carried by the frame 61 comprising part of a

so-called stitch-frame as usual in buttonhole sewing machines of the above type. This under thread mechanism comprises a throat-plate 7 having an opening through which the needle 62 of the under thread mechanism operates. The block 5 is also provided with the hollow stem or spindle 8 which is movable vertically in the block and by which the movements are given to the needle, 10 looper and other operative parts of the under thread mechanism. In devices of this nature the needle thread 9 for the under needle 62 extends up through the hollow spindle 8 and emerges from the opening 63 15 from whence it extends to suitable tension device (not shown) and thence to the needle, all as usual in sewing machines of the "Reece" type.

In my improvements I provide a construction whereby the stay-cord 10 which is laid around the edge of the buttonhole underneath the buttonhole stitches can be led up through the hollow spindle 8 and through a stay-cord grip device situated beneath the 20 work-supporting means and from which it is delivered to the opening through the throat-plate. For this purpose the spindle 8 is provided with a central partition 64 to form two passageways 11 and 65 there- 25 through through which the stay-cord and needle thread pass, respectively. At the bottom of the spindle I have placed a cap 12 which is provided with two openings 13 and 14 through which the stay-cord and 30 under needle thread pass, said openings being alined with the passageways 11 and 65. The stay-cord passes up through the spindle, out through the opening 63 in the block 5, and thence to a stay-cord grip de- 35 vice which is carried by the block 5 and which is best seen in Figs. 1, 3 and 5. In the present embodiment of my invention this thread grip device is mounted on an arm 15 which is secured to the stitch block 40 5 by means of suitable screws 16, said arm passing up through the bearing ring 70 and terminating just below and at one side of the throat-plate. The stay-cord-gripping device which is carried by this arm is here- 45 shown as constituted by two clamping members 17 and 18 which are pivoted to the upper end of the arm 15, as shown at 19 and 20, respectively. The member 17 is provided with an aperture 52 through which 50 the stay cord 10 passes, and with an opening 21 in which the nose 22 of the clamping member 18 operates. The clamping mem- 55 ber 17 is acted upon by a spring 23 which is connected to the arm 15, as shown at 24, 60 said spring normally tending to move the member 17 in a direction opposite to that in which the stay-cord is fed. The nose 22 is normally positioned at one side of a line connecting the centers 19 and 20, and the 65 length of the nose is such that when the

gripping members tend to swing downwardly into the position shown in Fig. 5, the nose 22 will grip the stay-cord 10 firmly. As the stay-cord is fed forwardly in the direction of the arrows *a* Fig. 5 the gripping members will also swing in the same direction sufficiently to release the gripping pressure on the stay-cord so that the latter may be freely drawn through the device. If, however, the stay-cord is drawn backwardly, 70 then it becomes firmly gripped by the nose or projection 22 and is prevented from backward movement. The stay-cord grip herein shown is also provided with a guide eye 49 through which the stay-cord is led to the 75 grip and to a roller 50 over which the stay-cord passes from the guide-eye to the gripping members. The arm 15 is shown as having two stop projections 240 and 25 which limit the swinging movement of the 80 clamping member 17. Since this stay-cord controlling device is fixedly secured to the stitch-block 5, it will rotate therewith and, therefore, the thread-gripping members from which the stay-cord is delivered will 85 always have the same position relative to the throat-plate in all positions of the stitch-block. Since the stay-cord is delivered to the lower end of the spindle 8 which is the axis about which the spindle turns, the turning movement of the stitch-block during the 90 operation of the buttonhole will not affect at all the position of the stay-cord relative to the throat-plate and will obviate any possibility of the stay-cord becoming tangled. 95

This invention is especially useful when used in connection with a sewing machine having the under thread clamping mechanism shown in my co-pending application Se. No. 864,187, filed September 29, 1914, 100 because said thread-clamping mechanism is mounted on the throat-plate at the place where the usual guiding groove has heretofore been formed to receive the stay-cord as the stitch-block rotates about its vertical 105 axis. 110

While I have shown herein a selected embodiment of my invention, I do not wish to be limited to the constructional features shown. 115

I claim:

1. In a buttonhole sewing machine, the combination with stitch-forming mechanism including an under thread mechanism, of means to deliver a stay-cord to the button-hole being stitched, and a stay-cord clamp carried by the under thread mechanism and having provision to permit the stay-cord to feed forwardly but prevent it from being pulled backwardly. 120

2. In a buttonhole sewing machine, the combination with upper thread mechanism and under thread mechanism, of a combined stay-cord guide and clamp carried by the under thread mechanism and operating to 125 130

- permit the stay-cord to be fed forward freely but preventing it from being pulled backwardly.
3. In a buttonhole sewing machine, the combination with upper thread mechanism and under thread mechanism, of a combined stay-cord guide and clamp comprising a spring-actuated guiding member through which the stay-cord passes, and a pivoted clamping member which permits the stay-cord to feed forward freely, but clamps it against backward movement.
4. In a buttonhole sewing machine, the combination with stitch-forming mechanism including a rotary stitch block provided with a throat-plate and carrying under thread mechanism, said stitch block having depending therefrom a hollow spindle provided with two thread passages extending longitudinally thereof to receive the under thread and stay-cord, respectively, of a stay-cord clamp carried by the block and situated between the upper end of the stay-cord thread passage and the throat-plate, said clamp having means to prevent backward movement of the stay cord.
5. In a buttonhole sewing machine, the combination with stitch-forming mechanism including a rotary stitch block provided with a throat-plate and carrying under thread mechanism, of a hollow spindle depending from said stitch-block and movable therein for operating the under thread mechanism, said spindle being provided with a longitudinally-extending stay-cord-receiving passage, and a stay-cord clamp carried by said block and provided with means to permit the stay-cord to feed freely forwardly but to prevent it from being pulled backwardly.
6. In a buttonhole sewing machine, the combination with stitch-forming mechanism including a rotary stitch-block provided with a throat-plate and carrying under thread mechanism, of a hollow spindle depending from said block and movable relative thereto to operate the under thread mechanism, said spindle being provided with a longitudinally-extending stay-cord-receiving passage, a stay-cord guide sustained by said block between the upper end of said passage and the throat-plate and having a fixed position relative to the throat-
- plate and means coöperating with said guide to prevent backward movement of the stay cord.
7. In a buttonhole sewing machine, the combination with work-supporting means, of under thread mechanism, stay-cord-controlling means situated beneath the work-supporting means and comprising a stay-cord-guiding member, and means coöperating with said guiding member to permit the stay-cord to feed forwardly freely but to prevent backward movement thereof.
8. In a buttonhole sewing machine, the combination with work-supporting means, of under thread mechanism, stay-cord-controlling means situated beneath the work-supporting means and comprising automatically-operative means to clamp the stay-cord and prevent backward movement thereof, said means yielding when the stay-cord is drawn forwardly to unclamp said stay cord and permit forward feeding movement thereof.
9. In a buttonhole sewing machine, the combination with under thread mechanism, of stay-cord-controlling means carried by the under thread mechanism and comprising a spring-pressed guiding member by which the stay-cord is guided, and means coöperating with said guiding member to clamp the stay-cord against backward movement while permitting forward feeding movement thereof.
10. In a buttonhole sewing machine, the combination with stitch-forming mechanism including a rotary stitch block carrying under thread mechanism, of a stay-cord clamp and guide carried by said block and presenting an upwardly-directed arm, a spring-actuated guiding member pivoted to said arm and provided with a guide and through which the stay-cord passes, and a clamping member coöperating with the guiding member to prevent backward movement of the stay-cord while permitting it to feed forward freely.

In testimony whereof, I have signed my name to this specification, in the presence of two subscribing witnesses.

FRANK ZALESKI.
